DESCRIPTION

FIG. 1 is a top perspective view of a storage container for contact lens, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof;

FIG. 9 is a sectional view thereof taken along line 9-9 of FIG. 6;

FIG. 10 is a reference view thereof showing a configuration of use covered by a packing wrap;

FIG. 11 is a reference view thereof showing another configuration of use covered by a cap; and

FIG. 12 is a reference view of the storage container for contact lens with the covering shown in FIG. 10 and with the storage container placed on a storage case; and,

FIG. 13 is a reference view of the storage container for contact lens with the covering shown in FIG. 11 and with the storage container placed on a storage case.

The broken lines in the drawings show environmental structure and multiplied storage containers, none of which form a part of the claimed design.
